UNITED STATES PATENT OFFICE.

CHARLES G. W. NITZ, OF WAUWATOSA, WISCONSIN.

SELF-CLEANING NEEDLE-VALVE.

1,289,234.

Specification of Letters Patent. Patented Dec. 31, 1918.

Application filed June 18, 1918. Serial No. 240,583.

To all whom it may concern:

Be it known that I, CHARLES G. W. NITZ, a citizen of the United States, residing at Wauwatosa, in the county of Milwaukee, 5 and State of Wisconsin, have invented certain new and useful Improvements in Self-Cleaning Needle-Valves, of which the following is a specification.

This invention relates to needle valves, 10 and more especially to those having valve cleaning features.

Primarily the invention consists in a main or inlet valve and a supplemental needle or outlet valve.

15 The invention also contemplates the employment of the supplemental or needle valve as a sprayer, and furthermore it contemplates the use of a cleaning pin in the jet opening of the sprayer.

20 Another object of the invention is to make provision for wear of parts.

Details are set forth in the following specification and claim, and attention is invited to the drawings wherein:

25 Figure 1 is a longitudinal sectional view of the entire valve,

Fig. 2 is a perspective detail of the needle on an enlarged scale.

The valve casing comprises a barrel 1 30 threaded internally and externally as shown, and having at its forward end a head 2. On the exterior thread travels a nut 3 which coacts with the head and with packing rings 4 which hold the barrel in the wall of any 35 member where this valve is to be used. On the other end of the barrel is a gland 5 containing packing 6, and through the same passes the valve stem 7 which is cylindrical and smooth at this point and has a handle 8 and 40 at its outer end. Further inward the valve stem is threaded as at 10, and yet further it is reduced as at 11, while its tip is tapered or slightly conical as indicated at 12. The bore of the barrel at the inner end of its threaded 45 portion is contracted to form a conical seat 13 for said tip, and through one side of the barrel is an inlet 14. Beyond said seat 13, the bore of the barrel is again enlarged into a chamber which opens out the extremity 50 of such barrel.

Seated rigidly in a socket 20 in the extremity of the stem is a needle 21 which projects loosely through the outlet 15 from the seat 13, and has its point 22 dome shaped 55 as shown in Fig. 2 or made conical. The numeral 25 designates a cup-shaped needle

casing which is adjustably secured to the inner end of the barrel by any suitable means, threads 26 being shown in the present instance in the chamber and around the casing 60 for adjustably connecting these elements, and internally this casing is provided with a tapered or conical seat 27 whose smaller end communicates with a jet aperture 28. Finally the tip of the needle point 22 carries 65 a cleaner pin 29 preferably made flat on its extremity as seen in Fig. 2, and the size of this pin is such that it does not completely close the jet opening 28.

The parts being assembled as seen, when 70 the handle is turned to retract the stem 7 the tapered tip 12 of the same comes off the seat 13 and permits liquid to flow from the inlet to said seat and through the outlet 15 into the interior of the cupped casing 25. 75 At the same time that the stem 7 is retracted, the needle 21 is retracted with it and its tip 22 is unseated; and therefore the fluid within the cupped casing 25 may now flow through the jet opening to the point of use, 80 being broken up by the presence of the pin 29 in the opening. The needle may be so set with respect to the stem that when the latter unseats to a considerable degree the needle will open to a lesser degree on account of the difference in taper of the valve 85 seats 13 and 27, and therefore the fluid within the cup is under some pressure and will be delivered through the jet aperture 28 in the form of spray, as it is broken up 90 by the pin 29. Moreover, should the tapered tip 12 of the stem wear, or should the seat 13 wear, the flow of fluid through the aperture 28 will yet be controlled by the point 22 of the needle coacting with the 95 seat 27 within the cup. Should the wear extend to such a degree that it is found the needle only is functioning, it is quite possible to adjust the cup with respect to the valve casing or barrel so as to restore the 100 relative position of parts. When the valve is again advanced to closed position, the pin is forced through the jet aperture in the direction of the flow of the fluid, and pushes out of the same any accumulations which 105 may have occurred, and therefore the use of this pin is twofold, it first breaks up the fluid into spray at the jet aperture and it next cleans said aperture each time the valve is closed.

110 The foregoing description and the drawings have reference to what may be con-

sidered the preferred, or approved, form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to set 10 cure by Letters Patent, is:—

In a valve of the class described, the combination with a barrel whose bore is tapered near its inner end to form a seat and enlarged beyond said seat into an internally 15 threaded chamber, the barrel having an inlet, and a cup-shaped casing externally threaded for adjustable mounting within said chamber, the bottom of the cup being

conical internally to form a valve seat in alignment with that mentioned and opening 20 through the cup in a jet opening; of a stem longitudinally adjustable within said barrel and coacting with its seat to form a main valve, a needle seated in the end of the stem and projecting through the main valve and 25 throughout the length of the cup and tapered at its extremity to contact with the seat in the cup, and a pin on the smaller end of the needle projecting through said jet opening.

In testimony whereof I affix my signature 30 in presence of two witnesses.

CHARLES G. W. NITZ.
